UNITED STATES PATENT OFFICE.

JOHN A. WEIS, OF CHICAGO, ILLINOIS, ASSIGNOR, BY MESNE ASSIGNMENTS, TO CONVENIENCE PRODUCTS CORPORATION, A CORPORATION OF ILLINOIS.

TELEPHONE ATTACHMENT.

Application filed October 22, 1927. Serial No. 227,936.

This invention relates to means for enhancing and extending the utility of telephones and for simplifying their operation and use. The main objects of this invention 5 are to provide, for telephones of the hook-switch type, an improved form of receiver carrying attachment; to provide such a device adapted and arranged to positively prevent downward slipping displacement, as by 10 gravity; to provide such a device of unitary character adapted to brace a desk telephone against tipping; to provide such a device adapted to positively prevent endwise slipping of the receiver in the holder part; to 15 provide such an attachment having means for holding a pad of writing paper in position, convenient for use; and to provide for the display of advertising on such an attachment.

20 Certain illustrative embodiments of this invention are shown by the accompanying drawings in which:

Figure 1 is mainly a side elevation of a desk telephone having attached thereto a 25 simple embodiment of the main features of this invention.

Fig. 2 is a front elevation of the telephone and attachment shown in Fig. 1.

Fig. 3 is a perspective view of a wall telephone equipped with a modified form of receiver carrying attachment having some 30 of the principal features of this invention.

Fig. 4 shows a modified form of desk telephone attachment having also a combination 35 brace and writing pad holder.

Fig. 5 shows a modified form of means for gripping the receiver.

Fig. 6 is a plan of a device similar to that of Fig. 4, except that the top is broken away, 40 as on the line 6—6 of Fig. 4, and the paper holder part is disposed at the right of the telephone.

Fig. 7 is a right-hand side view of the part 45 for supporting the paper and advertising represented by Fig. 6.

Referring first to Figs. 1 and 2, I here show my invention as applied to an ordinary desk telephone 1, the latter comprising mainly a base 2, a standard 3, a transmitter 4, a 50 circuit controlling switch-hook 5 and a cord connected receiver 6, the function and arrangement of which parts are well understood by everybody.

The attachment 7 comprises a bracket 8 55 with a receiver carrying arm 9 hinged there-

to at 10. Said bracket is detachably connected at 11 to the lower end of standard 3 in downwardly facing contact at 12 with said base 2, so that it cannot slip out of place by gravity. Said bracket extends forwardly and 60 upwardly and somewhat laterally from its point of support at 12 to the hinge point 19 substantially level with the hook 5.

The said arm 9 is manually swingable upwardly and forwardly from a rearward 65 switch-hook controlling position to a forward listening position and vice versa. In each position it is recumbent and when not in use it rests about horizontally on hook 5 as shown by the dotted lines on Fig. 1. The 70 outer end of said arm 9 has a clamp 13 to grip the receiver medially and a clip 14 to hook over the ear cap 15 and prevent endwise slipping of the receiver. Mutually co-acting stop means limit the forward swing of arm 9, a 75 shoulder 16 being formed on bracket 8 and an arm 17 on arm 9. I prefer a friction joint at 10, and with this in view the coacting faces of the bracket 8 and the arm 9 are made rough, as will be understood, so that the arm 9 will 80 stay set in an upright or nearly upright position whenever desired.

Referring next to Fig. 3, the invention is here shown as applied to a wall telephone 21. In this instance the modified attachment 22 85 comprises a bracket 23 and a carrying arm 24. Said bracket 23 is clamped rigidly and non-slidably to the transmitter support 25 as by means of yoke 26 and screws 27. Said bracket has a curved outstanding part on the tip of 90 which as at 28 the arm 24 is hinged about on a level with the switch-hook 29. The arm 24 on its free end is bent outwardly at 30 and at its tip is provided with clamping means 31 to grip the receiver 6. In use said arm 24 is 95 swung manually over and forward to its listening position and reversely to its hook controlling position, the latter being about horizontally recumbent, as shown in Fig. 3.

In the embodiment shown by Figs. 4 and 5 100 the combination attachment 36 is secured to a desk telephone as in Fig. 1. But here the attachment comprises a different form of bracket 37 and a modified arm 38. Said bracket 37 includes a horizontal member 39 105 provided with a clamp part 40 to grip the standard 3, a foot part 41 to bear downwardly on the desk, not shown, an upright part 42 to carry the hinge 43 for said arm 38, and a combination writing paper support 110

and advertising display means 43 also bearing on the desk. The paper support 43 includes an inclined upwardly facing part 44 to receive a pad of paper, not shown, which part has stop lugs at 45—45 and hook lugs at 46—46 to engage the pad. At the back of the paper support 44 is a receptacle 47 for the reception of a card 48 to display advertising and the like. As will be seen, the foot part 41 is well adapted to stabilize the device as a whole. The paper holder 43 braces against forward tipping and the toe part 49 braces against tipping rearwardly.

The bottom edge of the clamp part 40 has downwardly facing contact at 40' with the telephone base 2, substantially as in Figs. 1 and 2; so that when the user picks up the telephone by grasping the standard 3, for use while standing, the attachment cannot 20 slip out of place by gravity.

The resilient grip part 50 on the free end of arm 38 is best shown by Fig. 5. Here the spring clip 50, which is formed on or secured to the outwardly bent tip 52 of said arm, 25 is provided with a pair of short arms 53 to embrace the receiver crosswise and also a pair of elongated arms 54 to extend lengthwise over and embrace the listening end of the receiver. By this construction the receiver may be slipped into place without the aid of any tools or mechanical operations other than spring action. The clips 54 prevent any lengthwise displacement of the receiver in the holder 50.

The embodiment shown by Figs. 6 and 7 is mainly similar to that of Fig. 4, except that in the attachment 61 here shown the paper and advertising holder part is on the right-hand side of the telephone instead of 40 being on the left side where the receiver carrying part is located. In this instance the bracket 62 comprises mainly an upright 63, corresponding with part 42 of Fig. 4, a cross bar 64, corresponding with bar 39, and terminating in a clamp 65, a rigid arm 66 attached to the grip end of bar 64, a foot bar 67 extending from the lower end of upright 63 across in front of the telephone, and an inclined sheet metal body part 68, corresponding with 45 part 44, extending from arm 66 to bar 67. The clamp 65 is resilient and might serve alone in ordinary use, but in order to make the engagement with the telephone more secure a bolt 71 and a thumb nut 72 are provided. The holder 68 for writing paper 73 also has a pocket 74 to accommodate an advertising display card 48, visible through the window 75. It is to be understood that 55 this device as a whole is adapted for manufacture from sheet metal and that wherever two parts are joined together spot welding may well serve the purpose, though not actually shown on the drawings.

As will be apparent, many needs are met 60 by this invention, including; (1) enhanced

convenience and utility owing to the combined facilities accommodated; (2) simplicity of construction and operation and corresponding low cost to manufacture and maintain; (3) positive dependability for ready use at all times without need for readjustments; (4) freedom from danger of getting upset or out of order; and (5) freedom from any injury to the telephone or interference with its normal operation.

With each form of desk stand attachment shown the user may, if he desires, grasp the telephone standard in one hand above the bracket as when standing or reclining backward in a chair and still have the other hand so free for writing or for holding a cigar.

The forms shown in Figs. 4 and 6 are adapted for distribution as advertising specialties; or if desired current advertising service may be carried by the interchangeable cards 48, or 85 each sheet of paper 73 may bear advertising, as across the top.

Although only a certain few specific embodiments of this invention have been selected to illustrate the improvements herein set forth, it is to be understood that some of the details of the constructions shown may be altered or omitted without departing from the spirit of the invention as defined by the following claims.

I claim:

1. A desk telephone attachment comprising a bracket having means to engage the standard of the telephone and a receiver carrying arm hinged thereto for swinging manually 100 from a hook controlling position to a listening position and vice versa, said bracket having a downwardly disposed brace part to bear on the desk.

2. A desk telephone attachment comprising a bracket adapted for clamping to the standard of the telephone and a receiver carrying arm hinged thereto for swinging upwardly and forwardly from a rearwardly recumbent hook controlling position to a forwardly recumbent listening position and vice versa, said bracket having a brace part to extend over the base of the telephone and bear downwardly on the desk.

3. A receiver carrier for telephones of the switch-hook type, said carrier comprising a bracket adapted to be attached to the telephone and an arm hinged to said bracket for swinging the receiver forwardly to its listening position and reversely to its hook controlling position with the arm resting on the hook, said bracket being formed and arranged to have downwardly facing contact with a part of said telephone to prevent downward displacement of said carrier, the arm hinge being positioned in front of and substantially level with the telephone hook when said carrier is in place, said bracket having a screw clamp to secure the same against slipping on the telephone standard,

and said arm and bracket having means to limit the forward swing of said arm.

4. The combination with a telephone having a cord connected receiver, a switch operating hook, a transmitter and a support for said transmitter, of a receiver carrying attachment affixed thereto, said attachment including a bracket clamped rigidly to said support and a receiver carrying arm connected at one end to said bracket and having its other end attached to the receiver, said bracket having a part abutting downwardly against a part of said support to positively prevent downward slipping by gravity, and said arm and receiver being freely swingable upwardly and over from a recumbent hook controlling position to a reverse recumbent listening position and vice versa.

5. A receiver carrier for telephones of the desk-stand type, said carrier comprising a bracket adapted to be attached to the telephone standard and an arm hinged to said bracket for swinging the receiver forwardly to its listening position and reversely to its hook controlling position with the arm resting on the hook, said bracket being formed and arranged to grip the standard adjacent to the telephone base to prevent downward displacement of said carrier, the arm hinge being positioned in front of and substantially

level with the telephone hook when said carrier is in place, and said arm and bracket having means to limit the forward swing of said arm.

6. An attachment for desk telephones of the switch-hook type, said attachment comprising a bracket having means to engage the standard of the telephone and a receiver carrying arm hinged thereto for swinging from a hook controlling position to a listening position and vice versa, said bracket having a brace to bear on the desk and a holder adapted to carry a pad of writing paper to facilitate manual recording of the telephonic subject matter simultaneously with a conversa- 35
40
45

7. An attachment for desk telephones of the switch-hook type, said attachment comprising a bracket adapted for fastening detachably to the standard of the telephone and a receiver carrying arm hinged thereto for swinging from a hook controlling position to a listening position and vice versa, said bracket having a combination brace and paper holder part to rest on the desk to stabilize the device and to facilitate taking notes upon and simultaneously with a conversation. 50
